UNITED STATES PATENT OFFICE.

ALFRED F. MCCOLLUM, OF BLOOMSBURG, PENNSYLVANIA, ASSIGNEE OF THREE-FIFTHS
TO JAMES MAGEE, 2D, OF BLOOMSBURG, PENNSYLVANIA.

EDGE-BINDING MACHINE.

1,088,605.

Specification of Letters Patent. Patented Feb. 24, 1914.

Application filed September 6, 1911. Serial No. 647,923.

To all whom it may concern:

Be it known that I, ALFRED F. MCCOLLUM, a citizen of the United States, residing in Bloomsburg, Pennsylvania, have invented 5 certain Improvements in Edge-Binding Machines, of which the following is a specification.

My invention consists of a machine for forming and binding the edges of fabrics 10 and is particularly adapted for binding the edges of thick fabrics such as Wilton, Brussels and tapestry carpets and floor rugs, etc.

The chief object of my invention is to facilitate the binding of the edges of fabrics 15 such as shown and claimed in my co-pending application for U. S. Patent, Serial No. 647,924 filed Sept. 6, 1911, in which a turned edge is faced by a double folded binding strip and sewed to the body of the fabric.

Another object of the invention is that 20 the machine will be easily operated, durable and of a simple construction.

These objects I attain in the following manner, reference being had to the accompanying drawings, in which:—

Figure 1, is a side elevation of sufficient of 25 a sewing machine to illustrate my invention; Fig. 2, is an end view, partly in section; Fig. 3, is an end view, showing a different 30 position of certain of the working parts illustrated in Fig. 2; Fig. 4, is a plan view, partly in section, showing a rug being inserted and with the sewing machine arm removed; Fig. 5, is a plan view, showing the rug 35 inserted and the edge being formed; Fig. 6, is a sectional view taken on the line *a—a*, Fig. 1; Figs. 7, to 10 inclusive, are perspective 40 views of details of my invention; Fig. 11, is a transverse section on the line *b—b*, Fig. 10; Fig. 12, is a transverse section on the line *c—c*, Fig. 9; Fig. 13, is a transverse section on the line *d—d*, Fig. 9; Fig. 14, is a 45 transverse section on the line *c—c*; Fig. 9; Fig. 15, is an end view showing a spring-pressed brake, which I employ; and Fig. 16, is a perspective view showing how the binding strip and edge are folded and interlapped.

Referring to the drawings, 1 is the main 50 bed upon which is mounted the sewing machine arm 2, having a head 3. The head 3 contains the usual sewing elements including the reciprocating needle bar 4; needle 5; adjusting presser-foot rod 6; presser foot

6^a; take-up 7; presser-foot lever 8; and the 55 bobbin and shuttle mechanism 9.

A guide or alining plate 10 is slidably secured to the bed 1 and is provided with an extension 11, having a spring-pressed finger 12 and guide trough 12^a. The edge 13 of the 60 plate 10, together with the finger 12 and guide trough 12^a, act as alining surfaces for the outer edge 17 of the fabric, as the latter is fed through the machine.

A gage or guiding plate 14 has two arms 65 14^a adjustably secured to the bed 1 and is designed to extend over the fabric, as clearly shown in Fig. 5. The plate 14 is provided with a depending shoe 15 adjustably mounted thereon and adapted to engage and act as 70 an alining face for the inner edge 16 of the binding as the fabric is being fed through the machine.

The plate 10 is provided with a post 18, which passes through a slot 19 in the bed 1. 75 A cord 20 passes over anti-friction pulleys 21, 22, and connects the post 18 with a weight 23, so that the weight tends to move the plate 10 forward, as indicated by the arrows, Figs. 4 and 5. A bell crank lever 24 is pivoted at 80 25 to the bottom of the bed 1 and is connected by a link 26 to the post 18. A knee-plate 27 is formed on the lever 24 which, when pressed, will move the plate 10 rearward against the action of the weight 23.

A lever 28 is pivoted at 29 to the head 3 and normally rests on a lug 30, which is fixed on the bar 6. A coiled compression spring 31 is mounted on the bar 6 and contacts at one end with the top of the head 3 90 and at the other end with the lever 28. A projection 32, carried by the needle bar 4, is designed to strike and raise the lever 28 off of the lug 30, thereby relieving the presser foot bar of the action of the spring 31 when 95 the needle 5 has raised clear of the fabric. Another coiled compression spring 62 is mounted on the bar 6 and contacts with the top of the presser foot 6^a and the bottom of the head 3. Thus the spring 62 always exerts 100 a downward pressure on the presser foot irrespective of the position of the needle bar. Rock shafts 33 and 34 are provided with crank arms 35 and 36 respectively. A link 37, pivoted to the crank arm 35, is slotted at 105 38 and carries a spiked feed plate 39. A pin 40 on the crank arm 36 engages the slot 38 and tends, when the shaft 34 is moved, to

raise the feed plate into engagement with the fabric.

The arms 14^a of the plate 14 are so constructed that they will yield and thereby allow the shoe 15 to be deflected upwardly from its normal position due to irregularities in the thickness of the fabric passing thereunder. However, in order to keep the gage plate 14 and shoe 15 from being raised, 10 when the spikes of the feed plate 39 strike the fabric, or from any irregularity, which may occur when the fabric is passing thereunder, I provide a brace 41 which, in the present instance, is shown as a fork-shaped, 15 depending member adjustably secured at 42 to the head 3 and having its lower end contacting with the upper face of the plate 14. A box 43, filled with lubricating material, is interposed between the thread tension device 44 and the take-up lever 7; the said 20 tension device being of any serviceable construction. The thread 45, after passing through the tension device, passes through the lubricating material and around a 25 grooved pulley 46 which is mounted within the box 43.

A sheet metal feeding tube 47 is designed to doublefold a flat strip of binding tape and to turn the raw edge of the fabric, 30 which is to be bound, between the folds of the binding tape, as the latter is passing therethrough. At the end of the tube, indicated at *x*, Fig. 9, the cross section of the tape is substantially in a flat plane, slightly 35 rounded at the top, and is shown by dot and dash lines in Fig. 12. From the point *x* a wall 48 is bent away from the wall 49 and is curved, as shown at 50, Fig. 13. At the point *y* the outer wall 51 is turned to form 40 a spiral lap 51^a. An extension, or lip, 52, is formed on the portion 51 to insure that the tape takes the shape shown in dot and dash lines in Fig. 13.

A supplemental guide 53 is formed adjacent the point *y* and serves to turn the raw edge of the fabric 54, as shown in Figs. 13, and 14, so that the same will be within the folds of the tape when the latter passes out of the tube 47 and when it is sewed by the 50 needle 5. From the point *y* the portions 50 and 51 are gradually brought nearer each other until at *Z* they occupy the position shown in Fig. 14; a cross section of the tape assuming the shape shown in dot and dash lines and the relation of the fabric thereto being shown in full lines. The tube 47 is supported from an arm 55 on the bed 1 and is so positioned as to feed the taped edge of the fabric directly to the needle 5.

60 The binding strip or tape 56 is in roll form and is mounted on a turn table 57 pivoted on a spindle 58; the latter being fixed in a circular receptacle 59. The receptacle 59 is mounted on an extension of 65 the arm 55 and is slotted at 60 to form an

outlet for the tape. This slot is preferably so arranged that the tape, after passing therethrough, will be tangent with the outer surface of the receptacle and in alignment with the end *x* of the tube 47. A spring 70 plate 61 is secured to the receptacle 59 and bears against the tape so that the latter will not become slack if the roll of tape should happen to over-run, due to its inertia.

The operation is as follows:—After the free end of the binding tape 56 has been threaded through the tube 47, as shown in Figs. 4 and 16 the operator, by pressing the knee-plate 27, moves the plate 10 into the position shown in Fig. 4. The rug or other fabric to be bound is then inserted; the raw edge being slightly turned by hand under the portion 53, as shown in Figs. 4, and 16. The fabric and binding tape are then moved bodily to the sewing point *i. e.* under the 80 needle and above the spiked feed plate 39, and the knee plate 27 released to allow the weight 23 to slide the plate 10, finger 12, and guide trough 12^a into contact with the turned edge of the fabric so as to keep the 85 bound edge of the fabric in contact with the gage shoe 15, as shown in Fig. 5, and the machine started to stitch the binding tape to the fabric. The mechanism for actuating the several parts of the sewing machine is 90 not shown on the drawings, but may be of any well known construction that will impart a reciprocating motion to the needle, 95 presser foot and shafts 33 and 34. As the needle and bobbin operate in conjunction 100 to form a stitch, a movement of the shaft 34 in one direction, raises the spiked feed plate into contact with the fabric. Then a movement of the crank 35 in the direction of the arrow, Fig. 2, feeds the fabric. This 105 latter operation takes place after the needle bar has raised to such a height that the projection 32 thereon has lifted the lever 28 from contact with the lug 30 and thereby 110 compressed the spring 31 and relieved the 110 presser foot bar of the action thereof. Thus, when the spiked plate is feeding the fabric forward, the presser foot will only bear upon the fabric with the pressure of the 115 spring 62, which is slight and can be overcome by the feeding mechanism. As the needle bar descends to form another stitch the projection 32 will necessarily descend and allow the lever 28 to bear against the lug 30 with a pressure exerted by the spring 120 31. When the fabric is being fed forward by the spiked plate, only the spring 62 acts to keep the presser foot in contact with the fabric, but when a stitch is being formed the spring 31 serves as an auxiliary spring to 125 the spring 62 to form an increased pressure of the presser foot on the fabric.

After the spiked plate 39 has fed the fabric forward a predetermined distance to form the next stitch, the shafts 34 and 33 130

are then respectively moved in the opposite direction to that above mentioned. This latter operation withdraws the said spiked plate from contact with the fabric and returns it to its normal position, as shown in Fig. 2. As the edge is stitched and fed forward by the spiked feed plate, the tape will be drawn through the tube 47 and folded, as shown in Fig. 14, and the raw edge of the fabric will be turned in by the portion 53 of the tube 47 and will lie between the folds of the binding tape, as shown in Figs. 14 and 16. The spring-pressed finger 12, the guiding trough 12^a and face 13 of the alining plate 10, tend to keep the turned edge 17 straight and parallel with the bound edge 16; the latter being guided by the gage plate 14 and shoe 15. The members 12 and 12^a will yieldingly press against the line of turn of the fabric so that if there is any variation in the width of the turned portion of the fabric the positions of the said members will be automatically adjusted to suit such vibration. Thus, since the finger 12 is mounted on a spring and the trough 12^a is moved toward the turned edge by the weight 23, it is obvious that said finger and trough each constitutes an automatically adjustable means operative upon the fabric to move the turned edge of the latter between the folds of the binding strip.

In operation, the supplemental guide 53, after the edge of the fabric has been placed against the surface thereof, tends to gradually turn the edge of the fabric toward the binding strip folder or tube and as the fabric is fed, due to the regular feeding mechanism of the machine, the said edge will continue to be gradually folded or turned over. The guide trough 12^a acts as an auxiliary member to insure the turning of the fabric, so that no variation or vibration of the fabric will tend to move the turned edge of the fabric out of the path of the supplemental guide. The spring-pressed finger 12 serves to guide or press the turned edge within the fold of the binding strip as the latter is drawn from the tube or folder, thus insuring a positive and even inclosure of the folded edge of the fabric between the folds of the binding strip before passing between the alining face 13 of the plate 10 and the shoe 15 to be sewed. The resilient nature of the finger 12 and the fact that the alining plate 10 and guide trough 12^a are automatically movable against the edge of the fabric and capable of being moved away in an opposite direction should any irregularities or change of the width of the turned-over portion occur or be desired, renders the construction particularly efficient for binding turned-under edges of fabrics. The shoe 15 forms a positive and steady alining surface for the folded binding strip and as the binding strip folder or tube 47 in operation

is also rigidly mounted, all the lateral deviation is taken up by the movable members 10, 12 and 12^a.

By having the members 10, 12 and 12^a movable in a rearward direction by means of the lever or knee-press 27 any width or degree of turning of the edge of the fabric can be attained as the fabric when once turned and started between the guide trough 12^a and the supplemental guide will tend to keep at the same width during the entire binding and sewing operation, especially in binding stiff or rigid fabric or rugs, carpets or other heavy fabrics. However, variable size weights 23, or other means may be used to suit fabrics of different degrees of rigidity.

By having the fixed gage plate or shoe abutting the bound inner edge 16 and the slideable alining plate having points bearing against the turned fabric edge 17, a very even edge can be obtained, because the gage plate and alining plate define the path that the edge must take; thus substantially preventing lateral movement of the edge from its path as it passes under the needle.

To reduce the friction of the thread and needle and to prevent the temper of the latter being drawn when my machine is stitching a thick or closely woven fabric, the thread, as it passes through the lubricating box 43, receives a coating of lubricating paste. This latter it conveys to the needle. As the lubricating box is placed between the tension device and the needle 5, the lubricating material does not have time to soften the thread before the latter has lubricated the needle and has been stitched into the fabric. Thus the lubrication of the needle in the above described manner prolongs the life thereof by reducing the friction and does not injure the thread. The grooved pulley 46 and guide pin 64 tend to evenly distribute the lubricant over the thread.

To insure the bobbin casting its loop and to prevent the breaking of the thread on the bobbin, I prolong the needle slot 63 as shown in Figs. 4 and 5, so that the pull of the thread from the needle to the bobbin is never on the dead center. For example, if the slot 63 is made long the thread is allowed to take the movement of the feed which is sufficient when taken in a straight line tangent to the periphery of the bobbin to insure the casting off of the loop.

I claim:

1. The combination, in an edge binding machine for fabrics having sewing mechanism including a needle and feeding means, of a binding strip folder; means for turning the edge of the fabric; automatically adjustable means operable upon the fabric to move the turned edge of the fabric between the folds of the binding strip; and means for guiding the folded binding strip with the

125

130

turned edge of the fabric between its folds to the needle.

2. The combination, in an edge binding machine for fabrics having sewing mechanism including a needle and feeding means, of a binding strip folder; means for turning the edge of the fabric; automatically adjustable means operable upon the fabric to move the turned edge of the fabric between the folds 10 of the binding strip; an adjustable alining plate operable against the line of turn of the fabric; a shoe adjustably fixed on the machine and operable against the folded binding strip in conjunction with the alining plate to guide the folded binding strip with the turned edge of the fabric between its folds to the needle.

3. The combination, in an edge binding machine for fabrics having sewing mechanism including a needle and feeding means, of a binding strip folder; means for turning the edge of the fabric; automatically adjustable means operable upon the fabric to move the turned edge of the fabric between the 25 folds of the binding strip; an adjustable alining plate operable against the line of turn of the fabric; a shoe adjustably fixed on the machine and operable against the fabric and the folded binding strip in conjunction with the alining plate to guide the folded binding strip with the turned edge of the fabric between its folds to the needle; and adjustable means for limiting the upward movement of the shoe to keep the fabric in contact with the feeding means.

4. The combination, in an edge binding machine for fabrics having sewing mechanism including a needle and feeding means, of a binding strip folder; means for turning the edge of the fabric; an automatically adjustable alining plate operable against the line of turn of the fabric; an extension carried by the said alining plate; a guide trough supported on the extension and operable against the line of turn of the fabric; a spring-pressed finger mounted on the said extension and operable against the fabric to move and keep the turned edge between the folds of the binding strip; a shoe adjustably mounted on the frame of the machine and having an alining face oppositely disposed from the alining plate and operable against an edge of the turned binding strip, said shoe also having a face operable against the surface of the fabric, said shoe and the alining plate operating to guide the folded binding strip with the turned edge of the fabric between its folds to and past the needle.

5. The combination, in an edge binding machine for fabrics having sewing mechanism including a needle and feeding means, of a binding strip folder; means for turning the edge of the fabric; an automatically adjustable alining plate operable against the line of turn of the fabric; an extension car-

ried by the said alining plate; a guide trough supported on the extension and operable against the line of turn of the fabric; a spring-pressed finger mounted on the said extension and operable against the fabric to move and keep the turned edge between the folds of the binding strip; a shoe adjustably mounted over the frame of the machine and having an alining face oppositely disposed from the alining plate and operable against an edge of the turned binding strip, said shoe also having a face operable against the surface of the fabric, said shoe and the alining plate operating to guide the folded binding strip with the turned edge of the fabric between its folds to and past the needle.

6. The combination, in an edge binding machine for fabrics having sewing mechanism including a needle and feeding means, of means located forward of the needle for folding over the edge of a fabric; a binding strip folder located forward of the needle for folding the binding strip; automatically adjustable means operable against the line of fold of the fabric to move the turned edge of the fabric into the folded binding strip, said latter means including a guide trough for enveloping the line of fold of the fabric and a spring-pressed finger operable against the line of fold of the fabric; an alining plate, said guide trough and spring-pressed finger being located forward of the needle, said alining plate being located and extending from front to rear of the needle; and means operable upon the folded binding strip and the fabric and located forward and rearward of the needle and operable in conjunction with the said alining plate to guide the folded binding strip with the turned edge of the fabric between its folds to and past the needle, said guide trough and spring-pressed finger serving to move the turned edge of the fabric in between the folds of the binding strip.

7. The combination, in an edge binding machine for fabrics having sewing mechanism including a needle, of a guide for turning over the edge of the fabric; a folder for folding a binding strip; an automatically adjustable guide trough operable upon the fabric and serving to move and keep the turned edge of the latter between the folds of the binding strip; and means for feeding the folded binding strip with the turned edge between its folds to the needle to be stitched.

8. The combination, in an edge binding machine for fabrics or the like, of a guide for turning over an edge of a fabric; a folder for folding a binding strip; means operable upon the fabric to move the turned edge of the latter between the folds of the binding strip so that one edge of the binding strip is between the turned edge of the

5 fabric and the body of the fabric, said binding strip folder also serving to turn the other edge of the binding strip in between the body portion of the binding strip and the outer edge of the face of the fabric; and means for thereafter stitching the binding strip and fabric together.

9. The combination, in an edge binding machine for fabrics having sewing mechanism including a needle, of a guide for turning over the edge of the fabric; a folder for folding a binding strip; means operable upon the fabric to move the turned edge of the latter between the folds of the binding strip so that one edge of the binding strip is between the turned edge of the fabric and the body of the fabric, said binding strip folder also serving to turn the other edge of the binding strip in between the body portion of the binding strip and the outer edge of the face of the fabric; and means for guiding the folded binding strip with the turned edge of the fabric between its folds to the needle.

13. 10. The combination, in an edge binding machine for fabrics having sewing mechanism including a needle, of a guide for turning over an edge of the fabric; a folder for folding a binding strip; automatically adjustable means operable upon the fabric to move the turned edge of the latter between the folds of the binding strip so that one edge of the binding strip is between the turned edge of the fabric and the body of the fabric, said folder also serving to turn the other edge of the binding strip in between the body portion of the binding strip and the outer edge of the face of the fabric; and means for guiding the folded binding strip with a turned edge of the fabric between its folds to and past the needle.

11. The combination, in an edge binding machine for fabrics having sewing mechanism including a needle and a work feed, of a guide for turning over the edge of the fabric; a folder for folding a binding strip; an alining plate operable against the fabric; a resilient member operable against the fabric and serving to move the turned edge of the fabric between the folded binding strip; a guide trough operable against the fabric to aid in guiding the turned edge of the fabric within the folded portion of the binding strip; a member adjustably fixed to the frame of the machine and operable upon the fabric and inner line of fold of the binding strip; and automatic means operable upon the alining plate to move the latter against the fabric, said alining plate and said adjustably fixed member forming alining means for guiding the folded binding strip with the turned edge of the fabric between its folds to the needle so that it will be stitched to the body of the fabric.

12. The combination, in an edge binding

machine for fabrics, of means for turning the edge of the fabric; a folder for folding the binding strip; a movable alining plate operable against the fabric; a guide trough for engagement with the fabric and movable in conjunction with the said alining plate; a spring-pressed member operable against the fabric and also movable in conjunction with the said alining plate; a shoe adjustably fixed to the frame of the machine and serving to bear against the folded binding strip and located above the fabric; and means for automatically moving the alining plate toward the said shoe; said alining plate and shoe forming means for guiding the folded binding strip and the turned edge of the fabric between its folds to the needle.

13. The combination, in an edge binding machine for fabrics, of means for turning the edge of the fabric; a folder for folding the binding strip; a movable alining plate operable against the fabric; a guide trough for engagement with the fabric and movable in conjunction with the said alining plate; a spring-pressed member operable against the fabric and also movable in conjunction with the said alining plate; a shoe adjustably fixed to the frame of the machine and serving to bear against the folded binding strip; and means for automatically moving the alining plate toward the said shoe; said alining plate and shoe forming means for guiding the folded binding strip and the turned edge of the fabric between its folds to the needle, said needle being located between the shoe and the said movable alining plate.

14. The combination, in an edge binding machine for fabrics having sewing mechanism including a needle, of a guide for turning an edge of a fabric; a binding strip folder; means for moving the turned edge of the fabric between the folds of the binding strip; means for feeding the folded binding strip having the turned edge of the fabric therebetween to the needle; a movable alining plate; means for moving the alining plate against the fabric and toward the needle; a shoe adjustably fixed on the frame of the machine and bearing against the folded strip at points forward and rearward of the sewing point of the needle, said shoe and alining plate forming means for guiding the folded binding strip and the turned edge of the fabric between its folds to and past the needle.

15. The combination, in an edge binding machine for fabrics having sewing mechanism including a needle and feeding means, of means for turning the edge of the fabric; a binding strip folder; means for moving the turned edge of the fabric within the fold of the binding strip; a movable alining plate operable upon the fabric; means for

- automatically moving the alining plate against the fabric and toward the needle; a shoe adjustably fixed to the frame of the machine and operable against the folded binding strip to resist the pressure exerted by the said alining plate; means for moving the said alining plate in a direction away from the needle, said alining plate and the said shoe acting to guide the folded binding strip and the turned edge of a fabric between its folds to the needle.
16. The combination, in an edge binding machine for fabrics having sewing mechanism including a needle and feeding means, of means for turning the edge of the fabric; a binding strip folder; means for moving the turned edge of the fabric within the folds of the binding strip; a movable alining plate operable upon the fabric; means for automatically moving the alining plate against the fabric and toward the needle; a shoe adjustably fixed to the frame of the machine and operable against the folded binding strip to resist the pressure exerted by the said alining plate; means for moving the said alining plate in a direction away from the needle, said alining plate and the said shoe acting to guide the folded binding strip and the turned edge of a fabric between its folds to the needle; and means adjustably mounted adjacent the shoe and adapted to be engaged by the shoe to keep the fabric in positive contact with the feeding means.
17. The combination, in an edge binding machine including a needle, of means for supporting a strip of binding material; means for turning over an edge of a fabric; a binding strip folder; means for moving the turned edge of the fabric within the folds of the binding strip; a movable alining plate operable upon the fabric; means for automatically moving the alining plate against the fabric and toward the needle; a shoe adjustably fixed to the frame of the machine and operable against the folded binding strip to resist the pressure exerted by the said alining plate; means for moving the said alining plate in a direction away from the needle, said alining plate and the said shoe acting to guide the folded binding strip and the turned edge of a fabric between its folds to the needle.
18. The combination, in an edge binding machine including a needle, of a guide for turning over the edge of a body of fabric; means for applying a binding strip to the turned edge and yielding means movable into and out of engagement with the line of turn of the turned over edge of the fabric for alining the fabric, said yielding means being movable transversely to the direction of movement of the fabric and toward the needle.
19. The combination, in a binding ma-
- chine, of a guide for turning over the edge of a fabric; means for applying a strip of binding material to the said edge; means for sewing the said strip to the said turned edge and to the body of the fabric; and means for alining the fabric while it is being sewed, said latter means including guides having members engaging the outermost edge of the body of the fabric and the bound edge of the fabric respectively.
20. The combination, in an edge binding machine for fabrics or the like, of means for turning over the edge of the fabric; a binding strip folder; means for guiding the turned edge of the fabric in between the folds of the folded binding strip; a shoe adjustably fixed to the frame of the machine and bearing against the inner line of fold of the binding strip; an alining plate movably mounted on the frame and oppositely disposed to the said shoe; and automatically operating means connected to the alining plate to move the latter against the turned edge of the fabric and toward the shoe.
21. The combination, in an edge binding machine for fabrics having sewing mechanism including a needle and feeding means, of means for turning an edge of a fabric; a binding strip folder; means for placing friction on the binding strip before it is folded and sewed; means for moving the turned edge of the fabric within the folds of the binding strip; a movable alining plate operable upon the fabric; means for automatically moving the alining plate against the fabric and toward the needle; a shoe adjustably fixed to the frame of the machine and operable against the folded binding strip to resist the pressure exerted by the said alining plate; means for moving the said alining plate in a direction away from the needle, said alining plate and the said shoe acting to guide the folded binding strip with the turned edge of a fabric between its folds to the needle.
22. The combination, in an edge binding machine for fabrics or the like, of means for turning over the edge of the fabric; a binding strip folder; means for guiding the turned edge of the fabric in between the folds of the folded binding strip; a shoe adjustably fixed to the frame of the machine and bearing against the inner line of fold of the binding strip; an alining plate movably mounted on the frame and oppositely disposed to the said shoe; automatically operating means connected to the alining plate to move the latter against the turned edge of the fabric and toward the shoe; and means connected to the alining plate for moving the latter in a direction opposite to that in which it is moved by the said automatically operating means.
23. A strip folder through which a substantially flat strip of binding material is

- adapted to be drawn, said folder having a portion for folding over one edge of the strip, said portion being shaped to gradually turn the folded edge and the edge formed by the said folding of the said edge toward the opposite edge of the strip; and a strip threading lip extending from and forward of the said portion in the direction of the line of passage of the binding strip.
24. The combination in an edge binding machine including a sewing needle; of a receptacle containing a strip of binding material; a feeding tube through which the binding strip is passed; folding guides in the tube for double folding the binding strip as it passes therethrough; a supplemental guide for turning over an edge of a body of the fabric between the folds of the binding strip; and means for feeding the folded binding strip, with the turned edge between its folds, to the needle to be sewed to the turned edge and to the body of the fabric.
25. The combination in an edge binding machine including a sewing needle, of a receptacle containing a strip of binding material; a feeding tube through which the binding strip is passed; folding guides in the tube for double folding the binding strip as it passes therethrough; a supplemental guide for turning over an edge of a body of fabric and in between the folds of the binding strip; means bearing against the edge formed by the line of turn of the fabric and the binding strip to guide and aline the fabric to and under the needle; and means for feeding the folded binding strip, with the turned edge between its folds, to the needle to be sewed to the turned edge and to the body of the fabric.
26. The combination in an edge binding machine, of a supporting bed having sewing elements mounted thereon; a receptacle containing a strip of binding material; a feeding tube for folding the binding strip as the latter is passed therethrough; means for turning the edge of the fabric in between the folds of the binding strip; means for moving the folded binding strip, with the turned edge of the fabric between its folds, to the needle to be stitched to the fabric; a plate adjustably fixed to the bed; a shoe adjustably fixed to the said plate for engagement with the inner line of turn of the binding strip; means for preventing the raising of the said shoe as the fabric passes thereunder; a second plate slidably mounted on the bed; automatic means for moving the second plate toward said shoe; means for moving the second plate away from the shoe; a spring-pressed finger carried by the second plate to press against the edge of the fabric caused by the said turning of the fabric; a trough for guiding the turned edge of the fabric toward the tube; said shoe, trough and spring-pressed finger forming alining means for the folded binding strip and the edge of the fabric.
27. The combination in an edge binding machine, of a supporting bed having sewing elements mounted thereon including a needle; a receptacle for containing a strip of binding material and having a slot therein through which the said strip passes; a turn-table pivoted in the receptacle and upon which the binding strip is mounted; a spring brake mounted on the receptacle and adapted to press against the strip; a feeding tube for folding the binding strip as the latter is passed therethrough; means for turning the edge of the fabric in between the fold of the binding strip; means for moving the folded binding strip, with the turned edge of the fabric between its folds, to the needle to be stitched to the fabric; a plate adjustably fixed to the bed; a shoe adjustably fixed to the said plate for engagement with the inner line of turn of the binding strip; means for preventing the raising of the said shoe as the fabric passes thereunder; a second plate slidably mounted on the bed; automatic means for moving the second plate toward said shoe; means for moving the second plate away from the shoe; a spring-pressed finger carried by the second plate to press against the edge of the fabric caused by the said turning of the fabric; a trough for guiding the turned edge of the fabric toward the tube; said shoe, trough and spring-pressed finger forming alining means for the folded binding strip and the edge of the fabric.
28. The combination in an edge binding machine; of a supporting bed having sewing elements mounted thereon; a receptacle containing a strip of binding material; a feeding tube for folding the binding strip as the latter is passed therethrough; means for turning the edge of the fabric in between the fold of the binding strip; means for moving the folded binding strip, with the turned edge of the fabric between its folds, to the needle to be stitched to the fabric; a plate adjustably fixed to the bed; a shoe adjustably fixed to the said plate for engagement with the inner line of turn of the binding strip; means for preventing the raising of the said shoe as the fabric passes thereunder; a second plate slidably mounted on the bed; a weight; anti-friction pulleys; a post on the second plate; a cord connecting the post to the weight and passing around the pulleys; a knee-press lever pivoted to the supporting bed; means connecting the knee-press lever to the post; a spring-pressed finger carried by the second plate to press against one edge of the fabric; a trough for guiding the turned edge of the fabric toward the tube; said shoe, trough and spring-pressed finger forming alining means for the folded binding strip and the fabric.

29. The combination, in an edge binding machine for fabrics or the like, of stitching mechanism including a needle; a folder for folding a binding strip; means for turning an edge of the fabric in between the folds of the binding strip; with means automatically adjustable independently of the folder and the edge-turning means and operable on the line of turn of the said fabric for holding the said edge of the fabric between the folds of the binding strip while the latter is being fed to the needle.

30. The combination in a sewing machine including a needle, of means for turning the

edge of a body of fabric; an automatically adjustable alining plate operative against the line of turn of the fabric; and a shoe operable in conjunction with the alining plate and against the turned edge to guide the turned portion to the needle.

20

In testimony whereof, I have signed my name to this specification, in the presence of two subscribing witnesses.

ALFRED F. MCCOLLUM.
